UNITED STATES PATENT OFFICE.

CHARLES M. FOLLETT, OF MONTGOMERY, MICHIGAN.

FENCE-STAY.

No. 831,714.

Specification of Letters Patent.

Patented Sept. 25, 1906.

Application filed July 18, 1906. Serial No. 326,742.

To all whom it may concern:

Be it known that I, CHARLES M. FOLLETT, a citizen of the United States, residing at 5 Montgomery, in the county of Hillsdale and State of Michigan, have invented certain new and useful Improvements in Fence-Stays; and I do hereby declare the following to be a full, clear, and exact description of the invention, such as will enable others skilled 10 in the art to which it appertains to make and use the same.

My invention relates to new and useful improvements in fence-stays, and is adapted more particularly to be used in connection 15 with corner-posts and such other posts as are subjected to severe lateral strain; and my object is to provide means for retaining the posts rigid within the ground.

Other objects and advantages will be here- 20 after referred to, and more particularly pointed out in the claims.

In the accompanying drawings, which are made a part of this application, Figure 1 is a side elevation of a fence-post with my im- 25 proved stay secured thereto. Fig. 2 is an elevation of the lower end of the post, at right angles to that shown in Fig. 1. Fig. 3 is a central sectional view, on an enlarged scale, of the lower end of the post with one of 30 the retaining members thereon; and Fig. 4 is an elevation, partly in section, of the lower end of the stay, showing a slightly-modified form of retaining member secured thereto.

Referring to the drawings, in which similar 35 reference-numerals designate corresponding parts throughout the several views, 1 indicates a fence-post which may be constructed in any preferred manner and of any preferred material, but preferably composed of 40 metal and in tubular form, as shown.

Disposed upon the lower end of the post 1 and at any distance apart are trough-like retaining members 2, the post being directed centrally through said members, so that the 45 wings of the trough will project an equal distance from each side of the post, the members being held in position upon the post in any preferred manner, as by pins 3, extending through the post below the retaining mem-

bers, thereby preventing the post from being 50 pulled through the retaining members.

A stay-rod 4 is disposed at an angle to the post 1 and is secured thereto by means of a coupling 5, disposed around the upper end of the post 1 and having an angular socket 6 at 55 one side thereof, into which the upper end of the stay-rod 4 is inserted.

A coupling 7 is disposed around the post 1, adjacent the surface of the ground, with which is connected a brace-bar 8. The op- 60 posite end of said bar is directed into engagement with a coupling 9, disposed on the stay-rod 4 and in line with the coupling 7 upon the post. The lower end of the stay-rod 4 is pro- 65 vided with a plurality of inverted retaining members 10, which are held in place upon the rod 4 by means of pins or bolts 11, so that it will be impossible for the retaining members to move upwardly upon the stay-rods.

Instead of constructing the retaining mem- 70 bers in that form shown in Figs. 1, 2, and 3, said retaining members may be constructed as in Fig. 4 of the drawings, and, as shown in this view, the retaining members are con- 75 structed in the form of disks 12 and are se- cured in position upon the post and stay-rod by means of pins or the like 13, which are dis- posed at right angles through the stay-rod 14.

By this construction it will be seen that I have provided cheap and durable means for 80 securing the post and stay-rod rigidly in the earth, and any degree of strain may be com- pensated for by adding additional retaining members to the post and stay-rod.

What I claim is—

1. In a stay for fence-posts the combi- 85 nation with a post; of retaining members se- cured at intervals on the lower end of said posts, pins disposed through said posts and below said retaining members, a stay-rod 90 disposed at an angle to said post, means to secure said stay-rod to the post, a brace-bar connecting said stay-rod and post, a plurality of inverted retaining members on the lower end of said stay-rod and means to hold said 95 retaining members in their adjusted position.

2. In a stay of the class described the com- bination with a post having a plurality of

trough-like retaining members on the lower end thereof, and means to secure said retaining members on the post, a stay-rod disposed at an angle to said post, of means to secure said stay-rod to the post, a plurality of inverted trough-like retaining members on the lower end of said stay-rod and means to secure said members on the stay-rod.

In testimony whereof I have signed my name to this specification in the presence of two subscribing witnesses.

CHARLES M. FOLLETT.
